CARTRIDGE OR SHELL FOR CHAIN SHOT

John D. Forbes, San Francisco, Calif.

Application December 11, 1939, Serial No. 308,662

7 Claims. (Cl. 102—38)

My invention relates to improvements in a cartridge or shell for chain shot, and it consists of the combinations, constructions and arrangements hereinafter described and claimed.

An object of my invention is to provide a cartridge or shell for chain shot which is designed to make use of the different types of chain shot shown in my co-pending application Serial No. 298,259, filed October 6, 1939, now Patent No. 2,322,624, dated June 22, 1943. In the co-pending case I show chain shot composed of bars connected by links, the bars being foldable into a compact bundle in which the entire interior is a solid mass, giving weight to the projectile.

In the present invention, I provide three different types of cartridges or shells for housing the chain shot, all of the three shells being provided with fusible casings. One type of shell has a fusible casing which will melt from the gun blast heat and this will free the chain shot before it leaves the bore. In a second type of shell, a fusible casing is fired from the gun and is melted by a fuel contained within the casing. The fuel is set on fire by a fuse and the fuse in turn is ignited by the firing of the shell. The length of the fuse determines the time period between the firing of the shell and the fusing or melting of the metal casing enclosing the chain shot. The third type of shell differs slightly from the second. The fusible casing which is fired from the gun has a time dial which is used for igniting the fuse and melting the casing a predetermined time period after the shell is fired. With this shell, the time interval between the firing of the shell and the melting of the casing or bullet may be varied. The melting of the casing frees the chain shot.

Other objects and advantages will appear in the following specification, and the novel features of the device will be particularly pointed out in the appended claims.

My invention is illustrated in the accompanying drawings forming a part of this application, in which

Figure 1 is a horizontal section of a shell taken along the line 1—1 of Figure 2;

Figure 2 is a vertical section through Figure 1, a portion being shown in elevation;

Figure 3 is a horizontal section through a modified form of shell and is taken along the line 3—3 of Figure 4;

Figure 4 is a vertical section through the shell shown in Figure 3, a portion being shown in elevation;

Figure 5 is a horizontal section taken along 55

the line 5—5 of Figure 6 and showing another modified form of the invention;

Figure 6 is a vertical section through Figure 5, portions being shown in elevation;

Figure 7 is a detail view of the bar and link filler for the shell;

Figure 8 is a plan view of a closure used in the device shown in Figure 6; and

Figure 9 is a diagrammatic view showing one type of link filler or chain shot entirely expanded after the fusing of the shell casing.

In carrying out my invention, I will first describe the cartridge or shell A that has a casing which will melt when the shell is fired. The

shell is shown in Figures 1 and 2 and has a base 1 and a compartment 2 for receiving a chain shot indicated generally at 3. The wall 4 of the compartment 2 is made of a fusible metal that will melt from the heat created by the firing of

the shot. The base 1 contains a powder 5 which is ignited when the shell is fired and this forces a wadding 6 and a partition 7 against the chain shot 3 for firing the shot through the air. A disc 8 normally closes the top of the compartment 2.

In the firing of this type of shell, the metal casing 4 will melt immediately from the heat generated by the exploding powder 5. This will free the chain shot 3 and permit it to spread in the manner shown in Figure 9 and also as shown in my co-pending application. The shot when fully expanded will cover a wide area. The immediate release of the chain shot from the shell permits the device to be effectively used for short range firing. Such a shell is especially adapted for smooth bore grenade guns.

It is possible to form the metal casing 4 out of an alloy that will melt from the heat generated by the firing of the shell. For example, an alloy made from two parts of tin, three parts of lead and five parts of bismuth will melt at a temperature of 91° C., although the melting temperature of the three metals taken singly is much higher. Tin melts at 228° C., lead melts at 325° C. and bismuth melts at 264° C.

Another fusible alloy which could be used in the casing 4 consists of fifteen parts bismuth, eight parts lead, four parts tin and three parts cadmium. The fusing temperature of this alloy will take place at 100° C. Other alloys may be used and I have given these two particular alloys merely as examples.

In Figures 3 and 4 I show a shell B with a removable fusible casing 16 which is designed to be fired from a gun and then the shell casing,

housing the chain shot, will be melted at a predetermined time interval after the casing 16 leaves the gun. The powder 9 in the base of this shell 10 is separated from the chain shot 11 in the compartment 12 by a wadding 13 and a partition 14. A fuse 15 is disposed in the space between the wadding 13 and the partition 14 and one end 15a of the fuse extends through the wadding and contacts with the powder 9 while the other end 15b extends through the partition 14 and into the compartment 12.

The compartment 12 is enclosed by the fusible casing 16 which is made from an alloy that will withstand the heat from the temperature created by the firing of the shell, but which will be melted by a fuel 17 placed in the compartment. The top of the compartment 12 is closed by a cover 18.

When the shell B is fired, the end 15a of the fuse will be ignited by the burning powder 9 before the fusible casing with its shot 11 leaves the gun. The fuse will continue to burn while the casing 16 is traveling through the air and after a predetermined time interval, the flame will reach the end 15b of the fuse whereupon the fuel or powder 17 in the compartment 12 will be ignited. The burning of this fuel will create sufficient heat to melt the casing 16 and free the chain shot 11. The chain shot 11 will spread in the same manner as the chain shot 3 and will cover a wide area. The only difference between the two shells is the immediate freeing of the chain shot 3 in the gun barrel when the shell A is fired, and the subsequent freeing of the chain shot 11 after the casing 16 leaves the gun upon the firing of the shell B. In each case, the shell bases 1 and 10 remain in the gun after firing.

In the form of the device shown in Figures 5 to 8 inclusive, the material for melting the casing that leaves the gun is ignited by a fuse and the fuse in turn is set on fire after a predetermined time interval. A timing dial is used for igniting the fuse and this may be set for any time period desired. The cartridge or shell C shown in Figures 5 and 6 has a base 18 filled with powder 19 and this base remains in the gun when the shell is fired. A fusible casing 20 is removably carried by the base and a closure 21 is secured to the top of the casing. A central bar 22 extends between the bottom 23 of the removable casing 20 and the top closure 21 so as to transmit all thrust upon the casing 20, caused by the firing of the shell, directly to a head 24 of the casing rather than through the medium of a chain shot link filler 25 to the head. The pointed end 25 of the shell constitutes a dial which may be adjusted with respect to the head for setting fire to one end of a fuse 27 after the casing 20 has travelled through the air for a predetermined time interval. The means for setting the fuse on fire is not shown and it may be composed of any standard mechanism now used for that purpose.

The chain shot 25 mounted in the casing 20, is composed of a plurality of bars 25a interconnected by links 25b. The bars 25a disposed nearest the central bar 22 are connected to the closure 21 by members 26a. This type of removable casing 20 or bullet is designed to be rotated as it moves through the gun barrel, the rotation being caused by the rifling in the barrel. The rotation of the casing will cause the chain shot 25 to rotate therewith because the chain shot is connected to the shell by means of the members 26a

and is housed within the casing. When, therefore, the casing or bullet 20 melts, the chain shot will be freed from the casing compartment and will be spread due to the centrifugal force created by the rotating shell and members 26a. The central bar 22 has square portions 22a and 22b received in a square opening 23a in the casing bottom 23 and in a square opening 21a in the closure 21 for causing the head 24 to rotate as a unit with the bottom 23 of the casing. The bars 25a may be connected at their ends by the links 25b and they will form a spiral pattern somewhat similar to that shown in Figure 9 when fully spread out. This pattern will cover a large area, because the bars 25 will all be lying in the same plane. The bars 25 when expanded will not necessarily form a hexagonal spiral pattern although this is shown in Figure 9. The point to keep in mind is that a spiral pattern will be formed due to the rotation of the bar 22. In actual practice, a spiral will form and consist of a number of cords constituting the bars 25.

It is possible to fill the removable casing 20

with a powder 28 and pack this powder around the chain shot. The powder will be ignited by the fuse and will melt the casing 20 to free the chain shot after the bullet or casing 20 leaves the gun. One type of powder is Thermit. This alloy is composed of a mixture of finely divided metallic aluminum and one or more oxides, for example, iron. When the Thermit is ignited, it will create an extremely high temperature due to the result of the union of the aluminum with oxygen taken from the oxide. A powder for igniting the Thermit may be composed largely of barium peroxide and aluminum. The ignition powder 29 is placed between a shield 30 and the closure 21 and the fuse 27 extends down into this powder for igniting it. The powder 29 when ignited by the fuse, will generate a temperature of 1300° C., which is sufficient to ignite the Thermit 28 and cause the casing 20 to melt. The material forming the bars 25a is such as to withstand this high temperature. The powder and the Thermit will complete their burning in approximately one-half a minute. This type of shell is designed for long range duty where it is desired to free the chain shot after the shell has been fired into the air.

The casing or bullet 20 is made from an alloy that will withstand the firing temperatures of the shell, but which will be melted by the ignited Thermit. The Thermit will burn in an air-tight space and therefore the closure 21 need not be provided with openings 21b when Thermit is used. However, when other types of powder are used, it may be necessary to permit air to enter the enclosure and I therefore show the closure 21 in Figure 8 provided with openings 21b. The fuse 27 passes through one of these openings. The head 24 of the shell can have an opening 31 for feeding air to the openings 21b.

In Figure 7 I show a slightly different manner of connecting the central bar 22 to the adjacent bar 25a. The bar 22 has an annular groove 22c for receiving a link 25c that is in turn connected to the adjacent bar 25a. The other bars 25a are interconnected by the links 25b as shown. It is obvious that the heat generated by the Thermit when ignited, can be controlled and this is accomplished by changing the proportions of the compound. The speed of the reaction can also be decreased and a lower maximum temperature obtained by alloying the aluminum with lead or other metals that have a less powerful affinity

for oxygen than has aluminum. Thermit cannot be ignited by concussion or hammering because the ignition temperature of 1300° C. is too high. If, therefore, the powder 28 is Thermit, a special powder composed largely of barium oxide and aluminum is used in the manner already described. The fuse 27 will therefore ignite this special powder 29 which in turn will ignite the Thermit 28 and cause the casing 20 to melt.

While I have shown only the preferred forms of my invention, it should be understood that various changes or modifications may be made within the scope of the appended claims without departing from the spirit of the invention.

I claim:

1. A cartridge having a base for holding powder, a bullet removably carried by the base and having a cylindrical fusible wall, a chain shot disposed within the cylindrical wall and consisting of a plurality of bars linked together, one end of the chain shot being connected to the bullet, said bullet being rotated as it leaves the gun, means for melting the fusible wall while the bullet is in flight for permitting the chain shot to expand, the rotation of the bullet causing the chain shot to form into a spiral.

2. A cartridge including a bullet with a fusible cylindrical wall that will withstand the temperature created by the firing of the cartridge, a chain shot housed within the cylindrical wall, Thermit disposed around the chain shot, and means for igniting the Thermit for melting the wall.

3. A cartridge including a hollow bullet having a fusible wall, a chain shot disposed within the bullet, Thermit placed in the bullet adjacent said wall, an igniting powder placed with the Thermit, a fuse leading to the igniting powder, and adjustable time-delaying means for setting fire to the fuse at the proper time for igniting the powder and Thermit for melting the wall for freeing the chain shot.

4. In a device of the type described, an entirely enclosed casing having a continuous cylindrical wall and constituting a missile to be fired from a fire arm, a chain shot entirely housed within the casing, a fuel placed in the casing

around the chain shot for melting the casing and freeing the chain shot when the fuel is ignited, and delayed fuel igniting means for igniting the fuel a predetermined time period after the casing leaves the fire arm, whereby the casing is melted and the chain shot is freed.

5. A cartridge having a base for holding powder, an entirely enclosed fusible casing removably carried by the base and constituting a bullet, a chain shot entirely housed within the casing, a fuel placed in the casing for melting it and freeing the chain shot when the fuel is ignited, and a time fuse having one end contacting with the fuel and the other end contacting with the powder in the base, whereby a firing of the cartridge will ignite the fuse and the fuse will ignite the fuel a given time period after the bullet leaves the gun.

6. A cartridge having a base for holding powder, an entirely enclosed bullet removably secured to the base and comprising a head, a bottom, and a rod connecting the head and bottom together, the bullet closure including a fusible casing lying between the head and bottom, a chain shot placed in the bullet and freed when the fusible casing is melted, the rod communicating the thrust from the bottom of the bullet to the head when the cartridge is fired, delayed means for melting the casing after the bullet has left the gun a predetermined time period, said cartridge being rotated when fired, said chain shot being connected to the rod and extendible when the casing is melted to cover a wide area due to the rotation of the rod.

7. In a cartridge, a bullet having a base, a head, and a rod interconnecting the two for transmitting any thrust from the base to the head and for causing the head to rotate as a unit with the base, a fusible cylindrical wall enclosing the rod, said cartridge being rotated when fired, and means for melting the wall a predetermined time period after the bullet leaves the gun for permitting the rotating rod to form the chain shot into a spiral covering a large two-dimensional area.

JOHN D. FORBES.
